STOKER

Otto Moeller, Brooklyn, N. Y., assignor to The Standard Stoker Company, Incorporated, a corporation of Delaware

Application December 18, 1937, Serial No. 180,506

2 Claims. (Cl. 198—15)

My invention relates to stokers and particularly to stokers wherein a fuel receiving trough is movably mounted beneath a fuel bin and arranged to receive fuel therefrom through an opening in the fuel bin floor.

In constructions of this kind, it is usual to provide a sealing frame between the marginal edges of the opening in the bin floor and the open upper end of the stoker trough and it is an object of the present invention to provide in such construction an improved mounting arrangement of a sealing frame that is simple in construction, easily installed and that will permit the sealing frame to move freely with the stoker trough in any direction in a horizontal plane.

It is another object of the invention to provide in stoker installations of this kind, an improved construction and combination of elements, whereby the sealing frame between the fuel bin and the stoker trough is freely movable in any direction in a horizontal plane with the stoker trough and is arranged to eliminate leakage of fuel between the opening in the fuel bin floor and the sides of the trough as relative movement between the trough and fuel bin occurs.

With the above and other objects and advantages in view, the invention consists in the features of construction, the combination of elements and arrangement of parts hereinafter more fully described and claimed, and illustrated in the accompanying drawings, in which:

Fig. 1 is a longitudinal vertical section through adjacent portions of a locomotive and tender with a stoker, shown in elevation, applied thereto embodying a preferred form of the invention;

Fig. 2 is a sectional view on the line 2—2 of Fig. 1 in the direction of the arrows;

Fig. 3 is a sectional view similar to that shown in Fig. 2, illustrating a modified form of the invention;

Fig. 4 is an enlarged fragmentary sectional view on the line 4—4 of Fig. 2.

The invention has for purposes of illustration been shown applied to a stoker on a locomotive and tender, it being of particular advantage in such an installation; however, it will be evident from the following description that the invention is equally applicable to other types of stoker installations.

Referring now to Figs. 1, 2 and 4, which illustrate the preferred form of the invention, a locomotive is indicated generally by the numeral 10 and comprises a boiler backwall 11 having a fuel feed opening 12 therethrough, and a cab deck 13 extending rearwardly from the backwall 11 below

the fuel feed opening 12. A tender indicated generally by the numeral 14 comprises a frame 15 and a fuel bin 16 spaced thereabove and having a floor 17 forming a continuation of the tender deck 18.

The fuel bin floor is provided with a central longitudinally extending opening 19, which may be closed when desired by a slidably mounted plate 20, arranged to be drawn forwardly beneath the tender deck 18 to provide an opening 10 of a desired size.

Fuel is conveyed forwardly from the tender to the fuel feed opening 12 by a stoker, indicated as a whole by the numeral 21. The stoker 21 includes a transfer conduit 22 mounted at its rearward end in the compartment 23 beneath the fuel bin 16 and a forwardly and upwardly extending discharge conduit 24 communicating at its lower end with the forward end of the transfer conduit 22 and at its upper end with the fuel feed opening 12.

The transfer conduit 22 comprises an open mouth trough 25, arranged to receive fuel from the bin 16 through the opening 19, and a tubular portion comprising the telescopically connected conduit sections 26 and 27. The conduit section 26 is rigidly secured at its rearward end with the forward end of the trough 25, and the conduit section 27 is universally connected, as at 28, with the lower end of the discharge conduit 24.

The transfer conduit 22 is substantially straight along the vertical medial plane of its bottom inside surface and a screw conveyor 29 mounted in the transfer conduit advances fuel therethrough to the discharge conduit 24. The conveyor screw 29 is driven from its rearward end through gearing (not shown) in the gear housing 30 in a manner so well known in the art as not to require particular description. The fuel is elevated through the discharge conduit 24 in a manner well known in the art, to the fuel feed opening 12, where it is received by suitable distributing means, well known in the art, and projected in aerial paths over the fire.

The mounting arrangement for the trough 25 provides for lateral swinging movement thereof about a vertical axis and vertical swinging movement thereof about a transverse horizontal axis when relative movement between the locomotive and tender occurs, as in rounding curves or passing over switches and turntables. The mounting arrangement includes a plate 31 rigidly fastened to the frame 15 by suitable means, such as the bolts 32, and on which plate are rigidly fastened a pair of laterally spaced blocks 33 and 34, as by 55

the bolts 35. The adjacent upper portions of the blocks 33 and 34 are recessed as at 36 and 37, the upright walls 38 and 39 defining the recesses being curved and formed on the same radius.

5 A support member 40 is provided with a base 41 having an annular periphery fitting in the recesses 36 and 37 closely against the upright walls 38 and 39 that define the said recesses. The support member 40 can thus be rotated about the 10 vertical axis of the base 41, being at the same time fixed against bodily displacement in a horizontal plane. The support member 40 also comprises a pair of diverging arms 42 and 43 extending upwardly from the base 41 and spaced diametrically 15 opposite each other adjacent the periphery of the base 41. The free ends of the arms 42 and 43 are provided with the arcuate indentations 44 and 45 in which are rotatably mounted the shafts 46 and 47, carried by and extending outwardly from the 20 opposite lower sides of the trough 25. The trough 25 is thus pivotally supported by the support member 40 for movement about a horizontal, transverse axis and is movable with the support member 40 about the vertical axis of its base 41.

25 Since the trough 25 is movably mounted on the tender and therefore assumes various relative positions with respect to the opening 19 in the fuel bin floor 17, through which fuel drops into the trough 25, means is provided for preventing the escape of fuel between the sides of the trough and the fuel bin floor. This means comprises a sealing ring 48 which surrounds the opening 19 in the fuel bin floor 17 and extends downwardly from a position immediately beneath the fuel 30 bin floor into the upper portion of the trough 25 closely adjacent the walls thereof.

The sealing ring 48 is substantially rectangular in shape, having vertical side and end walls 49 and 50, respectively, flaring side and end walls 51 and 52, respectively, forming upwardly extending continuations of the vertical side and end walls 49 and 50, and horizontal flanges 53 and 54 extending outwardly from the upper edges of the flaring side and end walls 51 and 52, respectively. The upper edges of the flaring side and end walls 51 and 52 extend outwardly beyond the marginal edges defining the opening 19 in the fuel bin floor 17. Thus when the trough 25 swings laterally carrying with it the sealing ring 48, though the open upper end of the trough is out of register 45 with the opening 19, fuel will not escape but will fall on the flaring side and end walls 51 and 52 and be directed into the trough. A small space 55 is provided between the horizontal flanges 53 and 54 of the sealing ring and the underside of the fuel bin floor so that the sealing ring can move freely with the trough 25 without contacting the underside of the fuel bin floor.

Longitudinally extending brackets 56 and 57 rigidly secured by suitable means, as by bolts 58, to the side walls 59 and 60, respectively of the compartment 23 are provided for supporting the sealing ring 48. In the upper surface of the horizontally projecting arm 61 of the bracket 56 are formed the spherical indentations 62, one near the forward end and one near the rearward end of the sealing ring 48. In the indentations 62 are mounted ball members 63 on which rests a horizontal flange 53 of the sealing ring 48.

70 Similarly, in the upper surface of the arm 64

of the bracket 57 are formed the spaced spherical indentations 65 in which are mounted ball members 66 and on which ball members rests the other horizontal flange 53 of the sealing ring 48. The sealing ring 48 is thus freely movable in any direction in a horizontal plane as relative movement between the trough 25 and the fuel bin occurs.

In Fig. 3 is shown a modification of the means for movably supporting the sealing ring on the 10 supporting brackets. The construction in all other respects is identical with that of the preferred form of the invention and is therefore not described to avoid unnecessary repetition. In this construction casters 70 and 71, mounted 15 in the holes 72 and 73 in the horizontal flanges of the sealing ring and resting on the support brackets provide for movement of the sealing ring in any direction in a horizontal plane as relative movement between the trough and fuel 20 bin occurs.

I claim:

1. In a tender having a frame and a fuel bin having a floor with an opening therein, a compartment beneath said fuel bin and above said frame, a stoker fuel trough movably mounted on said frame and in said compartment with reference to movement about a vertical axis, a sealing frame having upstanding walls surrounding said opening and extending downwardly from the underside of said fuel bin floor into said trough adjacent the upper wall portions thereof and a peripheral flange at the upper end of said upstanding walls extending outwardly therefrom beneath the fuel bin floor, the upper surface of said peripheral flange being spaced from the fuel bin floor so that the sealing frame is movable with said trough in a horizontal plane without contacting the underside of said floor, said sealing frame being arranged to swing laterally with 30 said trough, a pair of laterally spaced brackets, one at each side of said trough secured to a respective upright wall of said compartment and anti-friction means interposed between said sealing frame and said brackets arranged to permit 40 said sealing frame to move freely in any direction in a horizontal plane. 35

2. In a tender having a frame and a fuel bin having a floor with an opening therein, a compartment beneath said fuel bin and above said frame, a stoker fuel trough in said compartment movably mounted on said frame with reference to movement about a vertical axis, a pair of laterally spaced brackets, one at each side of said trough secured to a respective upright wall of 50 said compartment, a sealing frame having upstanding walls surrounding said opening and extending downwardly from the underside of said fuel bin floor into said trough, said sealing frame being spaced from the underside of said fuel bin floor, the upper portion thereof being flared and its opening subjacent the fuel bin floor having a substantially greater cross sectional area than the cross sectional area of the opening in said fuel bin floor, and antifriction 55 means interposed between said sealing frame and said brackets permitting said sealing frame to move freely in any direction in a horizontal plane.
